UNITED STATES PATENT OFFICE

134,664

DESIGN FOR A COMBINATION BOTTLE CAP OPENER AND BRICKLAYER'S LINE PIN

Carl Nelson, Chicago, Ill.

Application October 23, 1942, Serial No. 103,603

Term of patent 14 years

To all whom it may concern:

Be it known that I, Carl Nelson, a subject of the King of Sweden, residing at Chicago, in the county of Cook and State of Illinois, have invented a new, original, and ornamental Design for a Combination Bottle Cap Opener and Bricklayer's Line Pin, of which the following is a specification, reference being had to the accompanying drawing, forming part thereof.

Fig. 1 is a perspective view of a combination

bottle cap opener and bricklayer's line pin, showing my new design;

Fig. 2 is a front elevational view, on a reduced scale; and

Fig. 3 is a side elevational view thereof.

I claim:

The ornamental design for a combination bottle cap opener and bricklayer's line pin, substantially as shown.

CARL NELSON.
